UNITED STATES PATENT OFFICE.

GUSTAVAS R. SIGNAIGO, OF MEMPHIS, TENNESSEE.

LIFE-SAVING APPARATUS FOR AVIATORS.

1,089,978.

Specification of Letters Patent. Patented Mar. 10, 1914.

Application filed April 30, 1913. Serial No. 764,652.

To all whom it may concern:

Be it known that I, GUSTAVAS R. SIGNAIGO, a citizen of the United States, residing at Memphis, in the county of Shelby, State of Tennessee, have invented certain new and useful Improvements in Life-Saving Apparatus for Aviators; and I do hereby declare the following to be a full, clear, and exact description of the invention, such as will enable others skilled in the art to which it appertains to make and use the same.

This invention relates to life saving apparatus for aviators.

The object of the invention resides in the provision of an apparatus of the character named which will be simple, light, compact and readily released when an emergency arises, and when so released will effect the descent of the aviator at a relatively low speed and thereby avoid the possibility of personal injury.

A further object of the invention resides in the provision of an apparatus of the character described which embodies an improved form of parachute, improved means for supporting the parachute upon the body of the aviator, improved means for releasing the parachute from the holding device which is harnessed to the aviator, and improved means for accelerating the spreading of the parachute when same has been released from the holding device.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a partial longitudinal section through an aeroplane showing the invention applied, the parachute of the apparatus being folded and supported upon the aviator through the medium of the holding device of the apparatus; Fig. 2, a plan view of the apparatus detached from the body of the aviator and with the parachute held in folded position; Fig. 3, a rear view of what is shown in Fig. 2 partly broken away; Fig. 4, a section on the line 4—4 of Fig. 3; Fig. 5, a detail perspective view of the apparatus showing one of the

pivoted members for holding and releasing the parachute, and Fig. 6, a perspective view partly in section and showing the parachute spread and in the act of descending.

Referring to the drawings the apparatus is shown as comprising a base plate 10 which has attached thereto a breast strap 11 and shoulder straps 12 and 13 whereby said base plate may be conveniently secured upon the back of the aviator as will be obvious. The holding device for supporting the parachute of the apparatus in a folded state comprises a U-shaped plate A which includes arms 14 and 15 the free ends of which are bent laterally and secured to the plate 10 in any suitable manner. The bight portion of the plate A is dished inwardly as at 16 so as to form a socket or seat for the reception of the parachute of the apparatus when the latter is in a folded state. The arms 14 and 15 of the plate A and also a portion of the bight of said plate are each slotted at spaced points and the portion of said plates between these slits is carried laterally to form a flat plate 17, the outer end of each of the plates 17 being directed toward and secured to the base plate 10. Pivotedly mounted on each plate 17 is an angle member B one arm 18 of which has a curved edge 18, while the corresponding edge of the other arm is beveled as at 19, the widest portion of said last named arm being disposed adjacent the plate 17. The pivot of each angle member B is extended through the adjacent plate 17 and has fixed thereon a lever 20 operating between the base plate 10 and the plate A. The free ends of each of the levers 20 are slotted as at 21 and engaged through these slots is a pin 22 carried by an operating bar 23 which is normally held in the position shown in Fig. 3 by a latch 24. By this construction it will be apparent that when the bar 23 is in the position shown in Fig. 3 the arms of the angle members B having the curved edge 18 will be disposed in a plane at right angles to the longitudinal axis of the plate A. Upon downward movement of the bar 23 it will be further apparent that the angle members B will be simultaneously rotated so as to dispose the arms of said members provided with a beveled free edge in a plane at right angles to the longitudinal axis of the plate A.

The parachute of the apparatus is shown as comprising a disk 25 to the periphery of

which is pivoted a plurality of ribs 26. These ribs are substantially arcuate in cross section and when folded have their adjacent edges disposed in overlapping relation, the 5 ribs in this folded position constituting substantially a cylindrical casing adapted to 10 seat snugly in the dished portion 16 of the plate A. The ribs 26 are connected to each other by webs 27 each of which latter is provided with a fabric extension 28 and these 15 extensions 28 are reinforced and connected to each other as at 29. In this manner the body of the parachute of the apparatus is formed. The outer edges of the fabric extensions 28 are connected to the breast strap 20 11 by means of cables 30 and it will thus be apparent that when the parachute just described is released and spread the body of the aviator will be supported thereby so 25 that his descent will be slow and the possibility of bodily injury entirely obviated. In applying the parachute same is first folded by lapping the extensions 28 and the web 27 within the ribs 26 so that same will assume the form of a cylindrical casing. This 30 resultant casing is then seated in the dished portion 16 of the plate A with the lower ends of certain of the ribs 26 resting on in-turned nibs 31 formed at the lower end of the plate A. The angle members B are then rotated to the position shown in Fig. 5 so that the curved edges 18 will embrace and hold the folded parachute to the plate A. Secured to the lower end of the bar 23 35 is one end of a cable 32 which has secured to its other end a ball 33. This ball 33 is normally embraced by the flexible fingers 34 formed on a bracket 35 secured to the body of the aeroplane.

40 With the apparatus secured to the aviator as shown in Fig. 1 it will be apparent that in case of an accident the aeroplane will drop more rapidly than the body of the aviator and as a result the cable 32 will draw the bar 23 downwardly before the ball 33 45 becomes disengaged from the fingers 34. This movement of the bar 33 will rock the angle members B and cause the beveled edges 19 of said members to wedge in behind the parachute and throw the same laterally and entirely free of the plate A. The ball 33 will then leave the fingers 34 and the

parachute will spread and safely land the aviator.

The spreading of the parachute is accelerated by means of springs 36 mounted in the disk 25 and bearing under tension against respective ribs 26 when the latter are in a folded state.

What I claim is:—

1. An apparatus of the class described comprising a base portion, straps connected to said base portion for supporting the latter on the body of an aviator, said base portion being provided with a groove, a folded 65 parachute seated in said groove, means for supporting said folded parachute against movement longitudinally of the body portion, means for normally holding the folded 70 parachute against movement laterally from its seat, and means operated by relative movement between an aeroplane and the body of an aviator for throwing said parachute laterally from its seat.

2. An apparatus of the class described 75 comprising a base plate, shoulder and breast straps connected to said base plate for supporting the latter upon the body of an aviator a U-shaped plate secured against said base plate and having its bight dished, a 80 folded parachute seated in the dished portion of the U-shaped plate, angle members pivoted on said U-shaped plate and each having the free edge of one arm curved and of the other arm beveled, the curved edges 85 of the arms of said angle members being adapted in the horizontal position of said arms to embrace and hold the folded 90 parachute against lateral movement from its seat and the beveled edges of the other arms of said angle members being adapted to wedge the folded parachute from its seat when said angle members are rotated in one direction, and means operated by relative movement between the aviator and aeroplane for rotating the angle members to wedge the parachute from its seat.

In testimony whereof, I affix my signature, in the presence of two witnesses.

GUSTAVAS R. SIGNAIGO.
